(57) **CLAIM**

The ornamental design for the dashboard with winged instrument panel as shown and described.

DESCRIPTION

FIG. 1 is a front, right perspective view of a dashboard with winged instrument panel showing a first embodiment of our new design;

FIG. 2 is a front view thereof;

FIG. 3 is a front, right perspective view showing illumination of the winged instrument panel; and,

FIG. 4 is a front, left perspective view showing illumination of the winged instrument panel thereof.

The broken lines in the figures show portions of the dashboard with winged instrument panel that form no part of the claimed design. The elongated dash lines in FIG. 3 and FIG. 4 indicate illumination and these lines form no part of the claimed design.
